DOOR CLOSER

Alan M. Lipschutz, Narberth, Pa.

Application June 10, 1957, Serial No. 664,552

4 Claims. (Cl. 16—59)

This invention relates to a door closer and check construction adapted to be used on a right-hand door as well as on a left-hand door without requiring rearrangement of its internal mechanism.

The door closer consists essentially of a housing containing a coiled clock type spring which is adapted to be selectively restrained at its inner end or at its outer end depending upon whether it is used on a right-hand or left-hand door. Means are provided externally of the casing which can be manually set to select the desired spring action.

Further details and advantages of the invention will be apparent from the following specification and accompanying drawings wherein:

Figure 1 is a vertical longitudinal section of the door closer,

Figure 2 is a sectional view taken on lines 2—2 of Figure 1,

Figure 3 is a view taken on lines 3—3 of Figure 1,

Figure 4 is a view taken on lines 4—4 of Figure 1,

Figure 5 is a perspective view of the double pawl used in the door closer shown in Figure 1,

Figure 6 is a perspective view of the spring driver used in the door closer shown in Figure 1, and

Figure 7 is a perspective view of the ratchet-wheel 51 and sleeve integral therewith used in the door closer shown in Figure 1.

Referring to the drawings, the casting which carries the closing and checking mechanism consists of a housing 30, which is provided with side wings 32, the latter having screw-holes 34 for attaching the closer to a door. Valve 14 controls the fluid by-pass flow in the cylinder 10 in a manner similar to the valve 13 of Taylor Patent 658,518.

The cylinder 10 is adapted to retain a suitable fluid and is closed by an end cap 11, internally threaded at 11a, and sealed by gasket 7. A piston 9 provided with a check valve of well-known construction to permit passage of the liquid in a well-known manner is adapted to reciprocate within the cylinder 10 and is actuated by a crank 16 which is connected to one end of a connecting link 17. The other end of link 17 is connected to pin 13 fixed in the piston 9. The fluid in the forward part 25 of the cylinder is adapted to be by-passed by adjustment of valve screw 14 which controls flow of the fluid.

The crank 16 is integrally connected to rotatable spindle 15 which extends through a bearing plate 75 which is threaded at its periphery 75a and is retained thereby in the annular juncture 30a of chamber 10 with housing 30. The bearing plate 75 is provided with a hub portion 77 which embraces the spindle 15 and is adapted to rotatably support a spring driver 60, shown in perspective in Figure 6. The spring driver 60 is provided with a sleeve 62 having a bore 63 through which the spindle 15 extends, as shown in Figure 1. The upper portion of the sleeve 62 is provided with two parallel flattened portions 64, as shown in Figure 6, for receiving an upper ratchet-wheel 50 which is provided with an opening having com-

2

plemental flattened portions 50a, as shown in Figure 3, adapted to slidably fit the flattened portions 64 of the sleeve 62. It will be evident that upon rotation of ratchet-wheel 50, spindle 15 will be rotated in the same direction, which in turn will operate the crank 16.

Referring to Figure 1, it will be seen that sleeve 62 is surrounded by a sleeve 54 which is free to rotate thereon. Sleeve 54 is integral with a ratchet-wheel 51, as shown in Figure 7, which is positioned below the upper ratchet-wheel 50, as shown in Figure 1. The ratchet-wheel 51 is provided with a lug 51a extending beyond its periphery, as shown in Figure 4, for a purpose to be explained later. A washer 53 is positioned between the two ratchet-wheels, the washer 53 having an outside diameter substantially equal to the outside diameter of lower ratchet-wheel 51. As shown in Figure 7, the sleeve 54 is provided with a longitudinal slot 54a which is adapted to engage and retain the inner end 70a of a coiled clock type steel spring 70, as shown in Figure 2. The outer end 70b of the spring 70 is adapted to be retained by a spring-retaining post 61 which is integral with the spring driver 60 as shown in Figure 6.

The housing 30 is provided with a vertically extending recess 33 for receiving a stop plate 85 which has a forwardly extending stop portion 86 extending within the housing. The stop portion 86 is adapted to be abutted by the spring-retaining post 61, as shown in Figure 2, so as to restrain the outer end 70b of the spring 70 against movement.

The upper end of housing 30 is closed by a frictionally retained cover 35 which is provided with two spaced downwardly extending lugs 5 which abut the side wings 32 and thereby prevent rotation thereof. Cover 35 is also provided with an upwardly extending lug 80 as shown in Figures 1 and 4, which is adapted to act as a stop for extension 51a of ratchet-wheel 51 for a purpose to be explained later. The cover 35 is provided with a central opening to permit the sleeve 54 of ratchet-wheel 51 to extend therethrough upwardly so as to permit ratchet-wheel to be rotatably supported on the shoulder portions 36 of the cover. As described previously, a washer 53 is positioned on ratchet-wheel 51 and the upper ratchet-wheel 50 is positioned thereover.

The upper end 15a of spindle 15 may be machined to give it an octagonal shape for receiving a complementary opening in one end of the closing arm 40 as shown in Figure 3. The arm 40 is securely retained on spindle 15 by a nut 49 threaded thereon against a washer 43. Arm 40 is provided with a pin 41 for rotatably retaining a double pawl 45 which is shown in perspective in Figure 5. The double pawl consists of an integral upper pawl 47 and an integral lower pawl 46. The double pawl 45 is adapted to be manually moved so as to selectively engage either pawl 46 with ratchet-wheel 51, or to engage pawl 47 with upper ratchet-wheel 50, depending upon whether the closer is to be used on a right-hand or left-hand door. Suitable indicia, such as 15', may be provided on the end of spindle 15, and suitable indicia, such as 40', on the end of arm 40, so that the arm 40 may be properly positioned on spindle 15 at any suitable angle to permit operation of the closer for either right-hand or left-hand door operation.

At the time of installation of the closer on a door, the spring 70 is suitably tensioned or pre-loaded by first manually rotating either ratchet-wheel 51 or ratchet-wheel 50 depending upon whether the door closer is to be used on a right-hand or left-hand door. The function of this pre-loading will be obvious from a detailed description of the operation of the closer to be given later.

When the door closer is to be used on a left-handed door, it is suitably attached to the door by screws through holes 34 in the plates 32. Then the spring 70 is pre-

loaded or tensioned to a suitable predetermined extent. This is accomplished by means of a suitable spanner wrench which is used to manually engage and rotate ratchet-wheel 51 in counter-clockwise direction, and likewise sleeve 54 integral therewith will also be rotated in the same direction. The inner end 70a of coiled spring 70, which is retained in the slot 54a of sleeve 54, will thereby be rotated and wound counter-clockwise while the spring-retaining post 61 will abut and thereby be fixedly retained against stop portion 86, thereby fixedly retaining the outer end 70b of the spring 70. Energy will thus be stored in spring 70 to pre-tension same to a desired degree. The pawl 46 is then manually pivoted so as to engage ratchet-wheel 51 and retain it against rotation whereby opening of the door will turn arm 40 and thereby wind up the inner end of said spring. Upon releasing an opened door to which the closer is attached, the stored energy of spring 70 will reverse the action of the parts previously described and thereby operate arm 40 which will act to close the door. Since lever arm 40 is attached to the upper end of the spindle 15 it will act to rotate the spindle when the door is opened and in turn operate the checking mechanism in a known manner. Likewise, when the door is being closed by the action of the stored energy in the spring this movement is regulated by the checking mechanism in a known manner. The pre-loading of spring 70 previously referred to in addition to the energy stored in the spring 70 by virtue of the opening of the door supplies the necessary energy required to close a door of given size and weight on which the closer is used.

When the door closer is to be used on a right-handed door, it is suitably attached to the door by screws passed through holes 34 in plates 32. The spring 70 is then pre-loaded or tensioned by manually rotating ratchet-wheel 50 in a clockwise direction by means of a suitable spanner wrench. Since ratchet 50 is engaged with the upper portion of sleeve 62, clockwise rotation of sleeve 62 will also result. The driver 60 will thereupon also be rotated in a clockwise direction and carry with it spring-retainer post 61 which will wind up the outer end 70b of the spring and store up energy in the spring. It will be evident that ratchet-wheel 51 will at the same time be rotated in a clockwise direction until lug 51a is stopped against lug 80 on cover 35, as shown in Figure 4. Upon release of an opened door to which the closer is attached the stored energy in the spring 70 will reverse the action of the parts previously described and thereby rotate arm 40 in a counter-clockwise direction and close the door.

The construction of the universal closer herein described is particularly advantageous on account of its simplicity of parts, each of manufacture and assembly durability and relatively low cost. The parts will not get out of order and will operate efficiently. The door closer furthermore has the advantage that the checking of an opened door will occur at about 85° from the closed position thereof for either right-hand or left-hand operation because the described construction in conjunction with the stored energy in the coiled spring 70 initiates hydraulic checking action at this angle.

It will be understood that the specific construction of the various parts of the door closer as herein described are intended to be an illustrative embodiment of the invention and that changes and modifications may be made which are intended to be included within the scope of the appended claims.

I claim:

1. A door closer comprising a casing formed to provide a cylinder and a spring chamber, a reciprocable piston in said cylinder, a spindle rotatably mounted in said casing,

said spindle being connected to said piston, a spring driver positioned in said spring chamber and having a sleeve portion and a spring-retainer post, said sleeve portion being rotatably mounted on said spindle, a ratchet-wheel having a sleeve portion integral therewith rotatably mounted on the sleeve portion of said spring driver, a coiled spring in said spring chamber, said sleeve portion of the ratchet-wheel being provided with a slot for retaining the inner end of said spring, a lug extending from the periphery of said ratchet-wheel, a cover on said spring chamber for closing same, a stop portion on said cover, said lug on said ratchet-wheel being adapted to be retained against said stop portion, whereby upon clockwise rotation of said ratchet-wheel so as to position the said lug of said ratchet-wheel against said stop portion the outer end of said coiled spring is free to be wound while the inner end of said coiled spring is fixedly retained in the slot of said sleeve portion to store energy in said coiled spring, the upper end of the sleeve portion of said spring driver being provided with at least two opposed flattened portions, a second ratchet-wheel positioned on said upper portion of said upper end of the spring driver sleeve portion, the said second ratchet-wheel being provided with an opening adapted to mate with the said opposed flattened portions and being rotatable therewith, a lever arm pivotally carried on the upper end of said spindle, a double pawl pivotally mounted on said lever arm, said double pawl having an upper pawl and a lower pawl adapted to be manually positioned and selectively engaged with the said ratchet-wheels, the lower pawl being adapted to be engaged with the said first-mentioned ratchet-wheel and the upper pawl being adapted to be engaged with said second ratchet-wheel, a stop portion retained in the wall of said spring chamber, said stop portion being adapted to retain the said spring retainer post against rotation in a counter-clockwise direction, said spring retainer post being adapted to retain the outer end of said coiled spring, whereby upon counter-clockwise rotation of said second ratchet-wheel the inner end of said coiled spring is free to be wound up while the outer end of said coiled spring is fixedly retained against said stop portion retained in the wall of said spring chamber to store up energy in said coiled spring, said door closer being adapted to be used selectively on a right- or left-hand door by manual adjustment of said double pawl.

2. A door closer as defined in claim 1, wherein a washer is interposed between the ratchet-wheels, the outer diameter of said washer being substantially the same as the outer diameter of the first-mentioned ratchet-wheel.

3. A door closer as defined in claim 1, wherein the casing is provided at its inner periphery with a longitudinally extending channel for slidably receiving a plate therein, said stop portion being integral with said plate and extending within the spring casing and adapted to be engaged by the spring-retainer post.

4. A door closer as defined in claim 1, wherein the upper end of the spindle is of octagonal contour and one end of the lever arm is provided with a complementary octagonal opening for receiving the upper end of the spindle, and indicia on adjacent portions of the upper end of the spindle and end of the lever arm for indicating predetermined positions of the lever arm with respect to the spindle.
